SWEATER DRIER

Donald C. Grant, Los Angeles, Calif.

Application May 28, 1942, Serial No. 444,808

4 Claims. (Cl. 223—69)

My invention relates generally to sweater driers and more particularly to a drier comprising an expandible frame, which may be adjusted to accommodate sweaters of various sizes.

As is well known, a sweater will dry approximately four times as fast and with a much better finish if stretched while drying to allow air to circulate around the individual fibers of the sweater. Various devices have been developed to stretch sweaters while drying, but so far as I am aware, they have all been cumbersome or complicated in structure, and not particularly satisfactory. It is consequently the major object of my invention to provide a sweater drier which is simple in construction and operation and which is readily adjustable to accommodate various sizes of sweaters.

It is also an object of my invention to provide a sweater drier which cannot possibly damage the fabric of a sweater and one, which because of its adjustability, can be used to either stretch the sweater beyond its normal size or allow the sweater to shrink while drying, these adjustments being possible in either direction.

One of the major advantages of my invention is that the drier can be inserted into a sweater having a small neck and then expanded to fit the sweater and allow it to dry in the proper shape.

Another object of my invention is to provide a sweater drier which because of its simplicity in construction is very economical to make and can be sold for a relatively low price so as to put it within reach of all who wish to buy.

Another object of my invention is to provide a novel clamping means for use in connection with adjustable frames, whereby the adjustment thereof is simple and sure.

These and other objects of my invention will become apparent from the following description of a preferred form thereof, and from the accompanying drawing in which:

Fig. 1 is a front elevation of my preferred form of sweater drier, showing it in expanded position inside of a sweater shown in dotted outline.

Fig. 2 is a view similar to Fig. 1, but showing the drier in contracted position preparatory to being removed from the sweater shown about it in dotted outline, and

Fig. 3 is a perspective view showing the adjustable clamping bracket and supporting means for the drier.

Referring now to the drawing, it will be seen that my drier comprises an expandible frame preferably formed of a single piece of relatively heavy flexible wire bent upon itself to provide

when expanded a support of the proper shape for the sweater being dried. It will be understood of course that while metal wire is now deemed the preferred material, wires made of plastic or other resilient material may be used in my invention and are broadly included in the term wire as used herein. The wire is first bent or otherwise formed upon itself to form a central section 10, which is preferably straight or horizontal, assuming the drier to be normally held in a vertical plane. The ends of the wire beyond the central section 10 extend upwardly to the points 11 and 12 where they are curved outwardly and then brought inwardly at the points 13 and 14, respectively. Above these points, the wires are again bent outwardly and then inwardly to cross each other with their ends 15 and 16 terminating on opposite sides. The vertical lengths of wire, each of which preferably follows a sinuous path as described will be herein generally referred to as the resilient legs of the frame which are joined at their lower end by the central section 10, the legs comprising shoulder portions 17 and 18, waist portions 19 and 20, and foot portions 21 and 22, respectively.

Referring now particularly to Fig. 3, it will be seen that I provide an inverted U-shaped resilient clamping bracket 23, the branches of which are slotted to provide individually compressible clamping elements which I have indicated as 24, 24A and 25 and 25A. Each of the clamping elements is provided with an aperture adjacent its lower end through which one end of the wire frame may be passed. The wire portion 26 which is the free end of the sinuous leg comprised of the portions 18, 20 and 22, passes through the apertures in the flexible clamping elements 24 and 25, while the wire portion 27 which is the free end of the vertical leg comprised of the portions 17, 19 and 21 passes through the apertures in clamping elements 24A and 25A. It will thus be seen that the sinuous legs cross each other at the top of the frame and since each top portion passes through only one set of clamping elements, each frame leg is adjustable independently by merely compressing the lower ends of the clamping elements through which it passes. The ends of the wire may be provided with protective coverings 28 and 29, respectively, so that they will not injure the fabric of a sweater if they become engaged therewith, and suitable supporting means which may take the form of a hook 30 may be provided to suspend the frame from any suitable support.

The operation of my device is as follows: Assuming the frame to be in compressed condition

as shown in Fig. 2 with the shoulder sections 17 and 18 at their innermost positions, and the free ends 26 and 27 extended to their outermost positions, the frame is slipped down through the neck of sweater 40 until the central section 10 is adjacent to or below the bottom of the sweater and the shoulder sections 17 and 18 of the frame are supporting the shoulders of the sweater. The lower ends of the clamping elements 24 and 25 are then compressed (i. e., moved in or squeezed towards each other) to free the wire portion 26 and said wire portion is pushed outwardly through the apertures to expand the shoulder section 18 and waist section 20 to engage the sweater. Clamping elements 24A and 25A are then compressed to free the wire portion 17-27 which is then pushed outwardly to expand sections 17 and 19 to engage the other side of the sweater and hold it firmly in drying position. In each case of course the resilient clamping elements are released as soon as the wire is in its proper position so that the wire portions are again clamped in position by frictional engagement with the aperture walls. The frame has now assumed the position of Fig. 1 wherein it will be seen that it closely conforms to the desired shape of the sweater which is properly held thereon in position for most efficient drying. The frame can then be hung from a clothesline or other support by means of the hook 30 until the sweater is dry.

If the sweater 40 is shorter than the frame, as shown in the drawing, and it is desired to stretch it vertically, it is a simple matter to attach a piece of cloth or other material to the lower end of the sweater and fasten it to the central portion 10 of the frame, thus pulling down on the sweater until the required tension has been exerted and the sweater is in the proper position for drying. Since sweaters when wet may be stretched considerably and will retain their shape when dry, to stretch a sweater with my device, it is merely necessary to expand the sinuous legs outwardly more than the normal amount to cause the sweater to assume a larger shape. Conversely, if it is desired to shrink the sweater somewhat, the sinuous legs are not expanded any further than necessary to properly support the sweater which is then allowed to dry in semi-shrunken condition which it will substantially hold after it has been removed from the frame.

From the foregoing, it will be seen that I have provided a sweater drier which is fully capable of attaining the advantages and accomplishing the objects previously stated, and while I have described a preferred form in considerable detail, it is to be understood that I do not wish to limit

myself to the form or materials shown but intend to include all patentable equivalents thereof as defined in the appended claims.

I claim as my invention:

5. A sweater drier, which includes: a wire frame formed with a generally horizontal central section, a pair of upstanding body sections formed to support a sweater, the upper portions of said wire passing each other so that the free ends thereof are on opposite sides, and a resilient U-shaped bracket having a central portion with a pair of legs on each side thereof, each leg being provided with an aperture adjacent its lower end, opposed pairs of said apertures being adapted to receive opposite end portions of said frame and adjustably hold the same, whereby by compression of opposed legs of said U-shaped bracket, said free ends of said frame may be individually adjusted to vary the shape thereof.
10. A sweater drier, which includes: a wire frame formed with a generally horizontal central section, a pair of upstanding body sections formed to support a sweater, the upper portions of said wire passing each other so that the free ends thereof are on opposite sides, and a resilient bracket having a central portion with a pair of legs on each side thereof, each leg being provided with an aperture adjacent its lower end, opposed pairs of said apertures being adapted to receive opposite end portions of said frame and adjustably hold the same, whereby by compression of opposed legs of said bracket, said free ends of said frame may be individually adjusted to vary the shape thereof.
15. A sweater drier which includes: a wire frame with a generally horizontal central section, a pair of upstanding body sections formed to support a sweater, the upper portions of said wire passing each other so that the free ends thereof are on opposite sides; and a bracket having two pairs of separate resilient clamping portions adapted to separately clamp opposite end portions of said frame and adjustably hold the same, whereby said free ends of said frame may be individually adjusted to vary the shape thereof.
20. A sweater drier which includes: a wire frame with a generally horizontal central section, a pair of upstanding body sections formed to support a sweater, the upper portions of said wire passing each other so that the free ends thereof are on opposite sides; and a bracket having a central portion with a pair of resilient legs on each side thereof adapted to separately clamp opposite end portions of said frame, whereby said free ends of said frame may be individually adjusted to vary the shape thereof.
25. A sweater drier which includes: a wire frame with a generally horizontal central section, a pair of upstanding body sections formed to support a sweater, the upper portions of said wire passing each other so that the free ends thereof are on opposite sides; and a bracket having a central portion with a pair of resilient legs on each side thereof adapted to separately clamp opposite end portions of said frame, whereby said free ends of said frame may be individually adjusted to vary the shape thereof.
30. A sweater drier which includes: a wire frame with a generally horizontal central section, a pair of upstanding body sections formed to support a sweater, the upper portions of said wire passing each other so that the free ends thereof are on opposite sides; and a bracket having a central portion with a pair of resilient legs on each side thereof adapted to separately clamp opposite end portions of said frame, whereby said free ends of said frame may be individually adjusted to vary the shape thereof.
35. A sweater drier which includes: a wire frame with a generally horizontal central section, a pair of upstanding body sections formed to support a sweater, the upper portions of said wire passing each other so that the free ends thereof are on opposite sides; and a bracket having a central portion with a pair of resilient legs on each side thereof adapted to separately clamp opposite end portions of said frame, whereby said free ends of said frame may be individually adjusted to vary the shape thereof.
40. A sweater drier which includes: a wire frame with a generally horizontal central section, a pair of upstanding body sections formed to support a sweater, the upper portions of said wire passing each other so that the free ends thereof are on opposite sides; and a bracket having a central portion with a pair of resilient legs on each side thereof adapted to separately clamp opposite end portions of said frame, whereby said free ends of said frame may be individually adjusted to vary the shape thereof.
45. A sweater drier which includes: a wire frame with a generally horizontal central section, a pair of upstanding body sections formed to support a sweater, the upper portions of said wire passing each other so that the free ends thereof are on opposite sides; and a bracket having a central portion with a pair of resilient legs on each side thereof adapted to separately clamp opposite end portions of said frame, whereby said free ends of said frame may be individually adjusted to vary the shape thereof.
50. A sweater drier which includes: a wire frame with a generally horizontal central section, a pair of upstanding body sections formed to support a sweater, the upper portions of said wire passing each other so that the free ends thereof are on opposite sides; and a bracket having a central portion with a pair of resilient legs on each side thereof adapted to separately clamp opposite end portions of said frame, whereby said free ends of said frame may be individually adjusted to vary the shape thereof.
55. A sweater drier which includes: a wire frame with a generally horizontal central section, a pair of upstanding body sections formed to support a sweater, the upper portions of said wire passing each other so that the free ends thereof are on opposite sides; and a bracket having a central portion with a pair of resilient legs on each side thereof adapted to separately clamp opposite end portions of said frame, whereby said free ends of said frame may be individually adjusted to vary the shape thereof.
